STAY BOLT

John Roger Flannery, Pittsburgh, Pa.

Application May 9, 1940, Serial No. 334,184

7 Claims. (Cl. 85—1.5)

My invention relates to staybolt assemblages, particularly for locomotive fire box boilers; and it is particularly directed to the construction of a staybolt, and to methods of testing a staybolt while it is in service.

In a locomotive boiler the water compartment is formed between two steel sheets that serve as the walls of the compartment. The two sheets are held in pre-determined spaced relationship by a large number of staybolts extending through the space between the sheets, and suitably anchored to the sheets at both ends of the bolts. The inner sheet is usually arch-shaped and covers the fire-box or combustion chamber. The outer sheet is also generally arch-shaped.

In order to provide a certain degree of adjustability between the two boiler sheets, so they may adjust themselves according to the relative temperatures existing under ambient temperature conditions, and under elevated operating temperature conditions, some of the bolts are so disposed as to provide a certain amount of pivotal movement at one end. That end has been selected as the head end of the bolt which is mounted for pivotal movement at the outer sheet of the boiler.

Two types of flexible bolts have been employed. One type is a bolt having a solid shank. The other type is a bolt having a passage of small diameter, on the order of three-sixteenths of an inch, extending axially throughout the length of the bolt shank, and slightly into, but not through, the head of the bolt.

In each case, the bolt is provided with a slightly enlarged head having a substantially spherical under surface which can pivotally adjust itself against a correspondingly shaped surface formed either in a hole in the outer sheet through which the bolt extends, or in a sleeve or cup that is welded or threaded to the outer sheet at the hole through which the bolt extends.

In each case that opening through the sheet is hermetically sealed. In the case where the bolt head rests in a concavity in the sheet itself, that opening is closed by a simple cap which is completely welded to the sheet around the opening in which the bolt head is seated. In the case of the sleeve that is welded or threaded to the sheet, the top of the sleeve, which is essentially a cup-shaped supporting element for the bolt head, is suitably closed, either by a threaded plug, or by a cover that is welded to the top of the sleeve.

The inner end of the bolt is threaded into a

correspondingly threaded hole in the fire box. That end of the bolt in each case is stationary. In order further to anchor that end of the bolt at the fire sheet, the end of the bolt is peened-over or riveted where it extends slightly through the fire sheet.

The rules of the Interstate Commerce Commission require locomotive boilers to be tested once every year. That test is performed by raising steam in the boiler, while it is otherwise filled with water, thereby to subject the boiler and the bolts to hydro-static pressure. When solid flexible bolts are used as staybolts to hold the two sheets, the rules of the Interstate Commerce Commission require removal of all of the caps covering the flexible bolts, and a subsequent hammer-testing of all of the heads of those solid staybolts every two years.

When flexible tell-tale bolts having tell-tale holes are in service, the bolts are tested every year at the time that the hydro-static test is applied to the locomotive boilers. If any of the tell-tale flexible bolts are fractured, water will be forced through those fractures during the hydro-static test, and into the tell-tale holes. That water will then come out through the end of the tell-tale hole at the fire sheet, and will indicate that the bolt is defective.

During operation, the hollow passages in these tell-tale flexible bolts frequently accumulate a great deal of dirt and rust or scale. In order therefore to procure a proper test of the bolts, the Interstate Commerce Commission rules require that the tell-tale holes be cleaned out so there will be no impediment to the free flow of any water from a tell-tale hole after it has been forced into a bolt passage through a fracture in the bolt shank or body.

This operation of cleaning out each one of the bolts is an expensive one. Moreover, it has frequently resulted in destroying the operativeness of a bolt, because the drilling or reaming tool used to clean out the bolt was sometimes operated deeper into the head of the bolt than the original passage, and thereby lengthened the passage more than was necessary. If, by chance, successive cleaning operations in any particular bolt were attended by excessive drilling, the passage would be open clear out through the head of the bolt and the bolt was then rendered unfit for service, and therefore had to be removed, even though the bolt shank or body was otherwise sound.

One of the primary objects of my invention,

therefore, is to provide a testing system that will simplify and make certain the testing operation and thus reduce the extremely high costs and ineffectiveness of the present testing method.

Another object of my invention is to provide a bolt and a testing system that will not only obviate the necessity for cleaning out the tell-tale hole, but that will utilize, and take advantage of any rust or scale that may be formed in a tell-tale hole by water entering through a fracture in the bolt body.

Another object of my invention is to provide a staybolt as a unit combination so that it may be tested while in position and in service, to determine whether the bolt is sound and may therefore be continued in service, or whether it is fractured and must be removed and replaced.

Another object of my invention is to provide a bolt embodying a testing element as a permanent part thereof, so that the bolt may be easily and readily tested while in position and in service.

Another object of my invention is to provide a flexible staybolt having an axial tell-tale hole, extending from the riveted end into, but not through, the head at the other end, with an element in the tell-tale hole, to serve as an electrode for an external testing circuit, while the bolt is in position and in service.

A further object of my invention, therefore, is to provide a new bolt construction in which a testing electrode is permanently sealed in the central passage of the bolt, referred to as the tell-tale hole, and in electrically insulating this electrode from the bolt, while permitting the external end of the electrode at the riveted end of the bolt to be so located as to permit an electrical connection to be made thereto by a testing instrument.

Another object of my invention is to provide a new testing electrode, as a new article of manufacture, that may be applied to the many flexible tell-tale bolts now in service, to take advantage of the benefits of my present testing system as described herein, and thereby reduce the cost of supervising and testing those many bolts now in service in the Nation's locomotives.

My invention may also be applied to rigid bolts, which are fixedly secured at both ends to the two sheets. In that case, a tell-tale hole may be provided at one end only, or at both ends but not clear through, or it may extend clear through the bolt.

The manner in which the bolt is disposed in its assemblage with its testing electrode is illustrated in the accompanying drawing in which,

Figure 1 is a vertical sectional view through a portion of two sheets of a locomotive fire-box held by a rigid bolt;

Figure 2 is a similar view showing the two sheets held by a flexible bolt with a cap over the bolt head;

Figure 3 is a similar view of a flexible bolt employing a sleeve for the bolt head;

Figure 4 is a view similar to Figure 2, with an insulated electrode disposed in the bolt, in accordance to my invention, to provide a testing element by means of which the condition of the bolt may be ascertained;

Figure 4-a is a simple schematic view of a unitary tester for the bolts;

Figure 5 is an enlarged view of the riveted end of a bolt, whether of the rigid or of the flexible type, with an auxiliary element for holding the end-plug of the electrode in position, against casual displacement;

Figure 6 is an end elevational view of the riveted end of the bolt in Figure 5, showing how the anchoring washer is spot-welded on the bolt;

Figure 7 is a view similar to Figure 5, except that the bolt is provided with a recess to interlock with the plug material as formed, or with a bonding material on a preformed plug;

Figure 8 is a side elevational view of an electrode of one form embodying my invention;

Figure 8a is an enlarged view of a portion of an electrode of another form embodying my invention;

Figure 9 is a view of the riveted end of a bolt, whether rigid or flexible, provided with a short interlocking recess to receive some material of the molded plug or some of the bonding cement on a preformed plug;

Figure 10 is a view of the bolt in Figure 9, after the application of the plug, or of the material that forms the plug;

Figure 11 is a view similar to Figure 10 with a small cup to limit the amount of plastic material that may be inserted in the tell-tale hole to form the plug;

Figure 12 is a view, similar to Figure 1, of a rigid bolt provided with a testing electrode at each end of the bolt; and

Figure 13 is a view of the riveted end of a bolt in which a removable plug is provided to entirely enclose the outer end of the testing electrode.

As shown in Figure 2, two sheets 10 and 11 of a boiler surrounding a locomotive fire box, are arranged to be held together by a plurality of spaced staybolts 12 which are usually threaded into the fire-box sheet 11 and disposed for flexible movement in the outer sheet 10.

The bolt 12 is provided with a shank or body 13, threaded at one end 14, and provided with an enlarged head 15 at the other end. The bolt 12 is further provided with a central axial passage, or tell-tale hole 16, extending throughout the length of the body, or shank, of the bolt, and slightly into the enlarged portion or head 15 of the bolt. The purpose of this tell-tale hole 16 is to enable a fracture in the bolt body to be readily indicated and detected by the presence and observation of any water that might seep through the fracture in the bolt body, from the water chamber between sheets 10 and 11, into and through the tell-tale hole 16, and then out through the end of the tell-tale hole.

The head of the bolt 15 rests in an opening 17 in the outer sheet 10, that is usually of part-spherical shape to receive the enlarged portion or head 15 which is also preferably shaped on its under surface to be part-spherical, to permit maximum freedom of adjustability. The head 15 is covered by a cap 18 that is welded around its contacting edge to the sheet 10, to provide a complete closure and hermetic seal around the head 15 and the opening 17, in the outer sheet 10.

As explained above, the rules of the Interstate Commerce Commission require each boiler to be tested once each year while in service. At that time, all flexible tell-tale staybolts are also tested. This test is performed by heating the water in the boiler compartment contained between the two sheets 10 and 11 to a pressure about twenty-five per cent above normal operating pressure.

If any bolt is fractured, the hydrostatic pressure should force the water to seep through from the water chamber or space 20 through the fracture and into the tell-tale hole of the bolt. In order to permit such seepage to flow freely to the open end of the tell-tale hole from which the

usual plug 21 is removed during this test, it is also a rule, of the Interstate Commerce Commission, that all tell-tale holes 16 must be clean and free of any obstruction throughout their entire length. It is therefore customary, before testing each locomotive's water chamber, to clean out all of the tell-tale holes of the flexible bolts, to insure free passage for any water seepage.

It is necessary to clean out those tell-tale holes for the test, since, in the case of a broken bolt, any water that might have seeped through a fracture in the bolt, during operation, might also have caused sufficient rust to close the tell-tale hole against further free flow of water that would otherwise still seep through the fracture. When each tell-tale hole is reamed out and cleaned throughout its entire length, the subsequent hydrostatic pressure that is generated during the test should be sufficient to cause the water to seep through the fracture into the tell-tale opening and then flow freely out of the hole into the fire-box, at the inner end of the bolt, to indicate the fractured condition of that bolt.

Although this cleaning-out operation may be necessary for the bolts, to insure free passage for any water that might be forced through a fracture in the bolt, so that such fractured condition can be indicated, such cleaning operation with its incidental cost is but one undesirable thing that my invention is intended to eliminate.

Another undesirable condition that may be even more disadvantageous, and even possibly harmful, under some instances, is the possibility of an accumulation of a hard sediment on the outside peripheral surface of a bolt and adjacent to the fracture, in such manner as to completely seal the fracture against water seepage, and thereby to indicate a false condition of soundness in the fractured bolt, by preventing seepage during the hydrostatic test. It is to prevent such a false indication of soundness in a defective bolt that is another of the objects of my present invention.

Thus, a defective condition due to a fracture in a bolt may first permit sufficient preliminary seepage of water through the fracture to rust the inside of the tell-tale hole of the bolt, and the rust would then act as a plug or barrier against further seepage during normal operation, although the bolt was unsound. Thereafter, during the time interval between the occurrence of the fracture and the time of testing, sufficient sediment from the water in the boiler might accumulate on the outside surface of the bolt, at, and around, the fracture, to prevent further seepage.

Consequently, even though the tell-tale hole would be cleaned out prior to the hydrostatic test, the sediment on the outside of the bolt might be sufficient in quantity to prevent any seepage through the fracture during the test. Thus, the actual defective condition of the bolt would be hidden, and the dangerous condition in the defective bolt would continue to exist for possibly another year until the subsequent test.

By means of my invention, however, when a fractured condition occurs, the first results of the water seepage into the tell-tale hole are utilized to establish an electric circuit condition which can then be tested and detected without requiring the cleaning out of the tell-tale hole. At the same time, the danger is obviated, of the possibility that the fracture may be externally covered sufficiently to prevent seepage, and a sound condition still indicated, even though the frac-

tured bolt still has its outer structure that may give way during service and establish a dangerous operating condition.

This condition of the fracture in the bolt shank, or body, is indicated in Figure 3 in which the body of the bolt 12 has a fracture 23 whose origin 24 on the outer surface of the bolt is completely covered and sealed by a hardened caked mass 25 of the mineral or salt ingredients of the water usually supplied to the locomotive boiler. This mass 25 takes the form of a hard and solid rock formation, which adheres closely to the outer surface of the bolt, and, in many instances, is sufficiently adherent to establish a complete seal that would prevent seepage of water to the fracture 24.

Thus, while the tests heretofore employed as required by the Interstate Commerce Commission rules have provided a safety measure, that test did not necessarily completely indicate the defective condition of bolts that might actually have been in fractured condition during the test period.

The rusty condition in the tell-tale hole, that might have been caused by seepage through the fracture, and that should be available as tangible evidence of the defective condition of the bolt, is thus destroyed without serving any useful purpose, under the procedure and conditions of present tests.

Thus, another object of my invention is to provide a bolt construction that will utilize a rusty condition that might be caused by initial water seepage through a fracture in a bolt, and obviate the necessity that heretofore obtained, of clearing out the tell-tale hole for testing.

In order to detect a first break down condition that results from a fracture and the consequent seepage of water through the fracture into the tell-tale hole, I propose to insert a metallic conductor 27 as an electrode into the tell-tale hole and seal it in that position in the tell-tale hole as a permanent electrode, initially completely electrically insulated from the bolt itself.

As shown in Figure 8, the electrode consists of an electrical conductor which is shown as a wire 28, covered by spaced insulating beads 29. The electrode is of any heat-resisting metal, such as, for example, Nichrome heating element wire. The electrode should be self-sustaining, but small enough to fit into the tell-tale hole when covered by the beads 29. The beads 29 are of any suitable material which will space and insulate the conductor 28 from the side walls of the tell-tale hole, and those beads may be made of clay or of other equivalent refractory insulating material. The sections of the conductor 28 between the beads are not insulated, but are left to be engaged by, and electrically conductive to, any water that might seep through a fracture in the bolt. The inner end of the electrode is covered by an insulating bead to prevent electrical contact with the body of the bolt at the headed end of the tell-tale hole. The outer end of the electrode 28 is preferably anchored and supported in a refractory plug 30.

In order to prevent turning in the plug, the conductor is provided with one or more bends or laterally extending portions 31 which will be anchored in the plug 30. A short extension 32 is provided at the outer end of the electrode, to serve as a terminal to permit the connection of external testing circuit to the electrode, to determine whether the insulated condition be-

tween the electrode and the bolt has been broken down and changed to a conducting condition.

The plug 30 may be made of a refractory material to be shaped as indicated as a truncated cone. In that case, the plug is shaped of proper size to fit into the conical opening 22 that is usually formed at the outer end of the tell-tale hole at the fire-box or riveted end of the bolt. That conical opening is usually formed at the end of the tell-tale hole when that end of the bolt is peened-over, as indicated in several of the drawings.

In order to hold the plug 30 of the electrode in position at the end of the bolt, I may resort to the arrangement shown in Figure 5, according to which an annular washer 35 is spot-welded or tacked to the end surface of the bolt on the outside of the plug, after the electrode and the plug have been placed in position. The washer 35 is arranged to be concentrically located so that the terminal 32 of the electrode will be spaced and insulated from the washer, and available for contact through the opening in the washer.

In Figure 7, I have shown another arrangement, whereby the plug for the electrode may be anchored in position. With this arrangement, after the end of the bolt has been peened-over as at 36, and the conical end of the opening 22 formed at the end of the bolt, an additional annular groove 37 is formed in the bolt near the outer end of the tell-tale hole. The plug 30 may then be formed of a moldable putty-like fire-resisting material and pressed into position so that some of the plug material will enter the groove 37, and there harden and become interlockingly anchored; or a portion of self-hardening bonding or cementing material may be added to the outer peripheral surface of the plug to be pressed into the groove 37 when the plug is forced into position, so that the bonding material, upon hardening, will form a key to lock the plug into position against casual displacement. The groove 37 need not, of course, be completely circular. Any recess to receive the bonding or plug material will suffice.

When the electrode is to be positioned in, and assembled with, the bolt, after the bolt has been placed in position, the electrode is cut to proper size to fit into the tell-tale hole, so that the electrode will occupy substantially the entire length of the tell-tale hole, and insulated from the headed end, when the plug is pressed into its tightest possible position to which it is to be anchored. The plug is then anchored either by some such mechanical arrangement as is shown in Figure 7, or by a self-interlocking arrangement such as shown in Figure 6.

When this electrode is disposed in the bolt, it may be left there for the life of the bolt. Thereafter, it is unnecessary to remove the electrode to clean out the tell-tale hole, as is the present practice in conformity with Interstate Commerce Commission rules. Thus, a great saving may be made by eliminating and obviating the necessity for such periodic cleaning out of the tell-tale holes.

A further advantage of the electrode of this type, that is permanently disposed in the tell-tale hole, is that immediately upon the occurrence of a fracture and the ensuing seepage of water through the fracture into the tell-tale hole, the insulated condition between the electrode and the bolt is disturbed, and it is changed to an electrically conducting condition due to

the presence of water in the first instance, or due to the presence of any rust that may be generated by the water in the tell-tale hole. In either case, the water or the rust will provide a conductor between the electrode and the bolt which will set up an electric short-circuit that may then be detected by a testing device, such as shown in Figure 4a.

The testing device which I have illustrated schematically in Figure 4a, comprises, briefly, a tubular contact or electrode 40, a scratcher or sharp-pointed terminal 41, a battery source of voltage 42, and a small incandescent lamp 43, all mounted upon, or enclosed within, a hand operable casing 44. The electrodes 40 and 41 are connected in series with the battery 42 and the lamp 43, so that when the circuit between 40 and 41 is closed, the lamp will be lighted by the voltage of the battery to indicate a closed circuit. Thus, when the tester is applied to a bolt, the electrode 40 engages the terminal 32 of the bolt electrode, and is then turned through a slight angle to permit the scratcher electrode 41 to scratch the surface of the peened-over edge of the bolt. If the tested bolt is sound, the main electrode 27 will be insulated from the bolt, and the circuit between electrodes 40 and 41 of the tester will not be electrically completed, and the lamp will not light. However, if the bolt is defective because of the presence of a fracture, sufficient to have permitted water to seep through and establish electrical contact between the electrode 27 and the bolt, the circuit will be completed between the electrodes 40 and 41 of the tester by the water or by the rust between the electrode and the bolt body, and the lamp 43 will be energized to light and indicate a closed circuit and therefore a defective bolt.

As I have already described above, the inner end of the electrode should be suitably covered in order to be insulated against electrical contact with the head of the bolt. In Figure 8, I have illustrated the electrode insulated by means of one of the long cylindrical beads by adding a cement or bonding material to that bead, or to any of the beads on the body of the electrode. The electrode may be anchored in position upon the drying of the bead and its consequent adherence to the engaged portion of the wall of the tell-tale hole. Thus, the electrode may be anchored by suitable anchoring means other than the outside plug or washer at the riveted end of the bolt.

Incidentally, although I have used the word "plug" for the sake of simplicity, throughout the specification and the claims, that word does not necessarily limit the invention to a single solid pre-formed closure for the riveted end of the tell-tale hole. The word "plug" is intended to be broad enough to include any type of a closure for the tell-tale hole with or without additional material for closing off or sealing the end of the tell-tale hole at the riveted end of the bolt. The closure material may be integral with the electrode before it is inserted in the tell-tale hole, or, as described above, is pressed into place as a plastic material, which hardens and anchors itself upon drying. To form the plug, or the plug material, I have utilized a high-temperature-resistant cement. A plug formed of such cement, or anchored by such cement, resists the temperatures of the flames in the fire box, and also forms a water-proof seal at the riveted end of the tell-tale hole.

In Figure 8, I have shown the beads held in

position, against axial sliding, by lugs 35 pinched or crimped on the wire at both sides of the beads. In Figure 8a, the wire section is slightly reduced at zones 36, and a mass 37 of refractory material, such as the above-mentioned cement, is molded on the wire 28 at those zones. Upon drying, those masses 37 become anchored in position.

In Figure 9, I have shown the electrode in position where a plug or closure is to be formed from plastic material such as the fire-resistant refractory cement. A short recess is formed in the bolt near the end of the tell-tale hole to receive a small amount of the plastic material, which will form a key upon hardening, to anchor the closure against casual displacement.

In Figure 10, the plastic material is shown in position with a tip of the electrode extending beyond a small recess in the plug material.

In Figure 11, I have illustrated an arrangement in which a small cup 50 is employed to limit the amount of plastic material that may be pressed into the end opening to prevent the pressure of that material, when inserted, from distorting the electrode 27.

In Figure 13, I have shown an arrangement whereby the plug may be preformed to serve as a complete closure for the end of the bolt without initially touching the electrode. In this case, the closure 41 is provided with an internal depression 52 to encircle, but not touch, the outer end of the electrode 27.

In Figure 1, I have shown a rigid bolt illustrated with two short tell-tale holes extending a short distance into each end of the bolt to a region beyond the thickness of the sheet. According to present practice, the tell-tale opening is provided in only one end of the bolt, at the fire sheet end. I contemplate, however, that the advantages of the present electrode, and the method of testing possible therewith, will make it advantageous to provide a tell-tale bolt from each end of the bolt, as in Figure 1, or even extending all the way through the bolt. When the hole extends only a part distance into the body or shank of the bolt, an electrode may be inserted at each end as in Figure 12. If the tell-tale hole is provided extending through the entire length of the rigid bolt, an electrode may be disposed to extend through the entire bolt, so a terminal of the electrode may be available for testing purposes at either end of the bolt. Each end of the tell-tale hole may then be sealed by any form of plug or closure shown in the various modifications illustrated.

My invention is thus applicable to all types of stay-bolts, whether of the rigid type or of the flexible type. With the testing electrode as I have described herein, it becomes unnecessary to clean out the tell-tale hole for testing purposes. In fact, the rust that results from water seepage through a fracture in the bolt becomes the medium whereby the insulated condition of the electrode is disturbed, so that a test of that condition of the electrode may be utilized to provide an immediate indication of the condition of the bolt.

My invention is not necessarily limited to any of the detailed arrangements or construction that have been shown, since they may be variously modified without departing from the spirit or scope of the invention as set forth in any of the appended claims.

I claim as my invention:

1. A new article of manufacture, for use with flexible staybolts having central axial tell-tale

holes, consisting of a metallic conductor having spaced-insulating means integrally secured thereon, said means having an external dimension small enough to permit the wire and insulating means to be inserted into the hole, with the inner end of the wire insulated from the corresponding end of the staybolt and a closure on one end of the metal conductor to anchor the metal conductor from the open end of the bolt hole.

5 2. A flexible staybolt provided with a concentric axial tell-tale hole, and having a metallic electrode insulatingly supported in the full length of the tell-tale hole by spaced beads on and secured to the electrode, with the inner end of the electrode insulated from the corresponding end of the staybolt, the electrode being anchored at the open end of the hole by an insulating closure through

10 which a portion of the electrode extends to serve as a terminal for an external testing circuit.

15 3. The combination with a flexible bolt having a tell-tale hole, of a metal electrode disposed in the tell-tale hole and insulated from the bolt body and head by spaced means along and around the electrode, an insulating closure fitting into the outer end of the tell-tale hole to close the hole and supporting the outer end of the electrode extending beyond the closure to serve as a terminal for an external testing circuit, and means integral with the bolt for holding the closure in

20 position.

25 4. The combination with a flexible bolt having a tell-tale hole, of a metal electrode disposed in the tell-tale hole and insulated from the bolt body and head by spaced means along and around the electrode, an insulating closure fitting into the outer end of the hole to close the hole and supporting the outer end of the electrode in a manner to permit the latter to serve as a terminal for an external testing circuit, and a recess near the end of the bolt for receiving and anchoring the closure in position.

30 5. A staybolt comprising a flexible bolt having a tell-tale hole, a metal electrode in the length 35 of the hole and spaced and insulatingly supported from the wall and head end of the tell-tale hole by spaced insulators on the electrode that establish small spaces to hold any water that might enter the hole through a fracture in the bolt body, a closure to close the open end of the hole and to support the outer end of the electrode, in a manner that will provide access to the terminal of the electrode by a testing instrument, and means to secure the closure against casual displacement.

35 6. A flexible staybolt assemblage, comprising the combination with two spaced sheets; of a bolt with an enlarged head anchored in a concavity in one sheet and threadedly anchored in 40 and riveted to the other sheet; a cap covering the enlarged head and hermetically sealed to the sheet to enclose the head and the concavity; a tell-tale hole in the bolt extending from the riveted end through the bolt shank and into, but not through, the head of the bolt; an electrode extending the full length of the tell-tale hole and insulatingly supported from the bolt body and from the front end of the bolt by spaced beads 45 on the electrode; and a closure closing the riveted end of the tell-tale hole and supporting the outer end of the electrode in such manner as to enable an electrical contact to be made thereto for an external testing circuit.

50 7. A staybolt assembly for a locomotive boiler,

comprising a bolt having a tell-tale hole extending axially into the shank of the bolt from one end that is to be riveted over to anchor the bolt in place; an electrically conducting electrode extending into and throughout the length of the tell-tale hole and electrically insulated from the bolt, and from the front end of the bolt, by spaced insulators on the electrode, with the end of the

5 electrode spaced from the bolt sufficiently to enable electrical contact to be made thereto for an external testing circuit; and a water-proof and fire-proof closure at the end of the tell-tale hole for sealing the hole against foreign matter except such as might enter through a fracture in the bolt along the length of the tell-tale hole.

JOHN ROGERS FLANNERY.
